UNITED STATES PATENT OFFICE.

JNO. HARRIS, OF LAWRENCE, MASSACHUSETTS.

SELF-ACTING MULE.

Specification of Letters Patent No. 13,752, dated November 6, 1855.

To all whom it may concern:

Be it known that I, JOHN HARRIS, of Lawrence, in the county of Essex and State of Massachusetts, have invented Improved 5 Machinery for Moving the Carriage of a Self-Acting Mule for Spinning Yarn; and I do hereby declare that the same is fully described and represented in the following specification and the accompanying drawings, of which—

Figure 1, denotes a top view of said mechanism; Fig. 2, a side elevation of it; Fig. 3, a vertical and longitudinal section of it; Fig. 4, an end view of it; Fig. 5, is a 15 side view of the eccentric gear to be herein-after described.

In specifying my invention I have not deemed it necessary to exhibit the carriage and main operative parts of a mule, the 20 machinery constituting my improvement being applied to the endless chain by which such carriage is usually put in motion or “run in” and “run out.” I have therefore merely represented such endless chain, and 25 my improved mechanism by which its movements in both directions are produced and controlled or regulated.

In the drawings above mentioned A, exhibits the endless chain sustained by and 30 working around two sprocket wheels B, and C, fixed respectively upon two shafts D and E, arranged parallel to one another and within a framework F, the said endless chain, when used being applied in the usual 35 way to the carriage of the mule. Above the chain there is arranged another shaft G (see Figs. 1 and 3), and carrying on its outer end a gear, H, and extending through a barrel gear, I,—such barrel gear is a cyl- 40 inder fluted on its curved surface, or pro- vided with long cogs and made to rotate freely upon the shaft, G, and barrel gear, I, there is a clutch K, by which the gear may 45 be clutched to the shaft as occasion may require. The sliding part α , of such clutch is moved longitudinally on the shaft and toward or away from the fixed portion, α' , by a forked lever, b, turning on a fulcrum, c, and jointed at its lower end to rod or bar, 50 d, whose other end is affixed to a collar, f, fastened upon a horizontal rod, L, the whole being arranged as seen in Figs. 1 and 3.

Operating in connection with the barrel 55 gear I above described, is an eccentric gear M fixed upon a shaft N, and arranged as

seen in the drawings. The said eccentric gear consists of a plate or disk having a circular row or range of teeth, g, g, extending from one side of it and so as to engage 60 with the teeth of the barrel gear, I, the said gear M, being arranged eccentrically upon the shaft N. There is fixed upon the said shaft N a bevel gear, O, which engages with another bevel gear, P, fastened upon 65 one end of an inclosed shaft, R, upon whose lower end there is attached another bevel gear S, which engages with the barrel gear, T, fixed upon the shaft E hereinbefore mentioned. On said shaft, E, there is a clutch, 70 U, by which a bevel gear, V, may be clutched to the shaft or unclutched therefrom as circumstances may require, the sliding part of 75 said clutch being operated by a bent shipper or lever, W, which turns horizontally upon a fulcrum, h, and is jointed to the slide rod, L, hereinbefore mentioned. The bevel gear, V, meshes into another bevel gear, X, fixed upon a shaft, Y, which carries on its outer 80 end a spur gear, Z, of the same size and number of teeth as the gear H hereinbefore mentioned. A pinion, i, fixed upon a horizontal driving shaft k, see Figs. 1, 3 and 4, engages with the spur gear, H, and with a similar connecting gear, l, which engages 85 with the gear, Z, hereinbefore mentioned. On the rod L, there is a slider, M', which has a set screw, n, by which it may be fastened at any desirable position on the rod. Enveloping the rod, L, and resting against 90 the said slider, M', is a helical buffer spring, o, against which and on the rod a collar, p, is placed—see Fig. 3.

When the above described machinery is 95 in operation, the shaft, k, is to have a continuous rotation in one direction. In consequence thereof the two gears X and H, and their respective shafts, Y, and, G, will be turned contrary ways. When the bevel gear H is clutched to the shaft E such shaft 100 will be rotated in one direction and with a regular movement and so as to produce a corresponding movement of the endless chain A. It is during this movement of the endless chain, that the carriage of the mule is “run out” and the spinning of the 105 yarn effected. When the chain is moved in the opposite direction, its movement is variable, or, in other words, it has first imparted to it a slow motion, and this while the “faller” of the mule is descending on the 110 yarn. Next the chain has a quicker mo-

tion which continues until the carriage has nearly completed its inward course. Finally, and during the remainder of the movement of the carriage, the chain has a continual and quick decreasing speed, the object of which is well known. The said last three movements of the chain are effected principally by the barrel gear I and the peculiar eccentric cam herein before mentioned. The barrel gear having a regular rotary motion turns the eccentric gear with first a constantly decreasing speed, and next a constantly increasing speed. Affixed to the endless chain A, is a slider S, which slides upon the rod L, and is alternately carried in contact with the collar f, and so as to produce the alternate shifting or movements of the clutches the barrel gear being unclutched with its shaft while the smaller gear on the shaft E is clutched to said shaft E. When the smaller bevel gear is unclutched from the shaft E, the barrel gear will be clutched to its shaft.

From the above it will be seen that by a very simple arrangement and combination of mechanism in comparison to that generally used for a similar purpose in mules, I am enabled to effect the variable movements of the carriage while it is running on and also effect the regular outward motion of it.

I do not claim combining with mechanism

for producing a regular backing off movement of the carriage, machinery not only for giving a slow motion to it, during the first part of its running in movement, or while the "faller" is descending on the yarn, a quicker movement afterward, or while the carriage is running in, but finally a slower movement decreasing to completion of the extent of inward movement of the carriage, but,

What I do claim is—

The peculiar combination herein before described and applied to the endless chain and for effecting such variable movement or "running in" of the carriage, the same consisting of the driving shaft G, the clutch apparatus thereof, the barrel gear I, the eccentric gear M and mechanism connecting the latter with the shaft E, of the endless chain, the whole being arranged and applied substantially as specified, to the mechanism for producing regular movement of the chain in a reverse direction.

In testimony whereof, I have hereunto set my signature the eighth day of October A. D. 1855.

JOHN HARRIS.
